UNITED STATES PATENT OFFICE.

DARIUS BANKS, OF MORRISVILLE, PENNSYLVANIA.

HALF-SOLE FOR BOOTS OR SHOES.

SPECIFICATION forming part of Letters Patent No. 351,953, dated November 2, 1886.

Application filed July 29, 1886. Serial No. 209,441. (No model.)

To all whom it may concern:

Be it known that I, DARIUS BANKS, of Morrisville, Bucks county, and State of Pennsylvania, have invented a new and Improved 5 Half-Sole for Boots or Shoes, of which the following is a full, clear, and exact description.

My invention relates to a half-sole for boots or shoes provided with a plate for attaching to the half-sole to the original instep-sole of the boot or shoe.

The invention consists of the special form of the plate, all as hereinafter described and claimed.

Reference is to be had to the accompanying drawings, forming a part of this specification, of which similar letters of reference indicate corresponding parts in both the figures.

Figure 1 shows a half-sole made in accordance with my invention, and Fig. 2 is a sectional elevation of the same, showing the half-sole attached to the instep-sole.

The half-sole A is made of leather, rubber, or composition molded into shape and formed 25 with a V-shaped recess at its rear, into which recess the metallic fastening-plate B is in-

serted. This fastening-plate B is formed with numerous perforations b, for the passage of pegs, nails, or other fastening devices for securing the half-sole to the instep-sole C and 30 to the foot or shoe. The plate B is bent to form the sharp portion a, which enters the V-shaped recess in the rear edge of the half-sole, and also to form the outer plate, a², which are spread apart to receive the edge of the instep- 35 sole C, as shown clearly in Fig. 2.

The main body of the half-sole is secured to the boot or shoe by the nails c, which, if the half-sole be molded from rubber composition, will be molded in and with the material com- 40 posing the half-sole.

Having thus fully described my invention, what I claim as new, and desire to secure by Letters Patent, is—

The half-sole A, provided with the fasten- 45 ing-plate B, formed with inner and outer plates, a a², to embrace the instep-sole, substantially as described.

DARIUS BANKS.
